UNITED STATES PATENT OFFICE.

GEORGE A. ARNDT, OF CHICAGO, ILLINOIS, ASSIGNOR TO EMIL G. JOHANSON, OF CHICAGO, ILLINOIS.

DESIGN FOR A HEADLIGHT-LENS.

52,503.

Specification for Design.

Patented Oct. 1, 1918.

Application filed May 8, 1918. Serial No. 233,397. Term of patent 7 years.

To all whom it may concern:

Be it known that I, GEORGE A. ARNDT, a citizen of the United States, residing at Chicago, in the county of Cook and State of Illinois, have invented a new, original, and ornamental Design for Headlight-Lenses, of which the following is a specification, reference being had to the accompanying drawing, in which—

Figure 1 is an elevation of the design; and Fig. 2 is a cross-section thereof.

I claim:—

The ornamental design for a headlight lens as shown.

In testimony whereof I affix my signature.

GEO. A. ARNDT.
